DESIGN FOR A GLIDER

Beverly Johnson, Dallas, Tex.

Application September 28, 1939, Serial No. 87,412

Term of patent 14 years

To all whom it may concern:

Be it known that I, Beverly Johnson, a citizen of the United States, residing at Dallas, in the county of Dallas and State of Texas, have invented a new, original, and ornamental Design for a Glider, of which the following is a specification, reference being had to the accompanying drawing, forming part thereof.

In the drawing:

Fig. 1 is a front perspective view of the glider

with the chair portion in normal position, showing my ornamental design;

Fig. 2 is a rear perspective view thereof with the chair portion tilted forwardly.

The dominant features of my design reside in the base members.

I claim:

The ornamental design for a glider, substantially as shown and described.

BEVERLY JOHNSON.
